S. S. Wheeler.
Hat Pounding Mach.
N°. 94,158. Patented Aug. 24, 1869.

United States Patent Office.

SIDNEY S. WHEELER, OF DANBURY, CONNECTICUT, ASSIGNOR TO
EDWARD A. NICHOLS, OF YONKERS, NEW YORK.

Letters Patent No. 94,158, dated August 24, 1869.

IMPROVEMENT IN HAT-POUNCING MACHINES.

The Schedule referred to in these Letters Patent and making part of the same.

To all whom it may concern:

Be it known that I, SIDNEY S. WHEELER, of Danbury, in the county of Fairfield, and State of Connecticut, have invented certain new and useful Improvements in Hat-Pouncing Machines; and I do hereby declare that the following is a full and correct description thereof, reference being had to the accompanying drawings, and to the letters of reference thereon.

My improvements relate to that class of hat-pounding machines in which a quick-cutting rotating cylinder or cone is applied to a hat-body placed upon a slowly-rotating hat-block.

The object of my invention is to apply a rapidly-rotating pouncing-cutter cylinder or cone to a hat placed upon a horizontal spindle, which rotates in fixed or stationary bearings, so that without moving the hat-block, except to rotate it, the operation of pouncing the hat may be performed, the mechanism which carries the pouncing-cutter cylinder or cone being so constructed as to adapt the position of the pouncing-cylinder to all parts of the hat-body, placed upon the hat-block, as required.

The first part of my invention consists in combining, with the rotating hat-block and pouncing-cylinder, a jointed arm or frame, substantially as hereinafter described, which carries the rotating pouncing-cylinder or cone, and is provided with a suitable handle, whereby the operator can apply the rotating pouncing-cylinder to any part of the hat placed upon the hat-block; second, in combining, with the jointed arm, carrying the pouncing-cylinder, a counterbalancing weight, to relieve the operator from the weight of the jointed arm.

But in order to more particularly describe my invention, I will refer to the accompanying drawings, of which—

Figure 1 is a side elevation, and

Figure 2 a plan view of the machine.

Letter *a* represents the frame of the machine; *b*, the hat-block, mounted upon a horizontal spindle, rotating in fixed bearings *b*¹ *b*², and carrying a pulley, *b*³, driven by a belt, *b*⁴, (fig. 1,) from any suitable pulley, on a countershaft overhead.

The jointed arm or frame *c* is pivoted horizontally upon the centre-pins *c*¹ *c*², and counterbalanced by the weight *d*, suspended from the bent arm *d*¹, so that the operator can move it up or down with a slight exertion of force applied to the handle *e*.

The hinge-joint *f* enables the arm to be moved laterally, that is, horizontally, toward and from the hat-block, and the swivel-joint *g* enables the forked part of the arm, which carries the emery-covered pouncing-cylinder or cone *h*, to be turned around at pleasure, so as to present the rotating pouncing-surface, at any desired angle of inclination, to the axis of the hat-block.

The pouncing-cylinder or emery-covered cone *h* is mounted on a short spindle, which rotates in bearings *h*¹ *h*² in the forked part of the jointed arm, and carries a pulley, *i*, driven by a belt, *j*, from a wide pulley, *k*, fast to a shaft which rotates in fixed bearings *k*¹ *k*², and carries a driving-pulley, *k*³, to which power may be applied by a belt, as usual in machinery.

When not in use, the jointed arm may rest upon the curved bracket-support *m*.

In operating the machine, the operator places the hat upon the rotating hat-block, and, taking hold of the handle of the jointed arm, applies the rotating pouncing-surface to the tip and sides of the hat at pleasure, until the operation is completed to his satisfaction.

I claim as of my invention and improvement in machines for pouncing hats—

1. The employment of the horizontal double-hinged and swivelled arm or frame, which carries the rotating pouncing-cylinder or cone, in combination with a horizontal rotating hat-block and the pouncing-cylinder or cone, substantially as described.

2. In combination with the hinged arm and pouncing-cylinder, a counterbalancing weight, or its equivalent, substantially as described.

SIDNEY S. WHEELER.
